UNITED STATES PATENT OFFICE.

MARTIN A. JOHNSON, OF STOUGHTON, WISCONSIN.

DESIGN FOR A TONGUE-CAP.

SPECIFICATION forming part of Design No. 21,459, dated April 12, 1892.

Application filed February 18, 1892. Serial No. 422,040. Term of patent 14 years.

To all whom it may concern:

Be it known that I, MARTIN A. JOHNSON, a citizen of the United States, residing at Stoughton, in the county of Dane and State of Wisconsin, have invented and produced a new and original Design for Tongue-Caps; and I do declare the following to be a full, clear, and exact description of the invention, such as will enable others skilled in the art to 5 know which it appertains to make and use the same, reference being had to the accompanying drawings, and to the letters of reference marked thereon, which form a part of this specification.

15 My invention relates to vehicles; and its object is to improve the appearance of the tongue-cap, which is the metallic piece covering the end of a wagon tongue or pole. This cap not only serves to protect and strengthen 20 the end of the pole, but it also gives it an ornamental appearance, which is very desirable in wagons and sleighs.

The leading features of my design are a ribbed top plate and a peculiarly-bent bottom plate 25 united by a curved end loop.

In the drawings, Figure 1 is a perspective view of my newly-designed tongue-cap. Fig. 2 is a top plan view thereof, and Fig. 3 is a cross-section on line 3 3, Fig. 2.

30 My tongue-cap has a top plate A, which extends along the upper side of the pole. It has parallel edges and its rear end is cut in a graceful curve. The plate is convexo-concave, in order to fit the outside of the pole.

35 Along its middle runs a rib or corrugation a.

The bottom plate B is about half as long as the top plate. It is made of a strip of metal flat on top and rounded beneath. The rear portion b lies flat against the pole and is fastened thereto. Forward of this the plate is 40 inclined downward at b', and then turns vertically upward at b² till it meets the pole. Then it extends along the pole at b³, then turns vertically downward at b⁴, though not to so great a depth as at b², then inclines upward and forward at b⁵ till it meets the pole again, and thence it runs along the pole b⁶ to the front end thereof, where it is drawn into a round rod, which is carried forward and upward in a semicircular loop C to meet the 50 top plate, to which it is welded at c at the point where the edges of the top plate converge to meet the rib a. The size of this rib is such that it seems to form a prolongation of the loop C. The sides of the upper plate 55 are drawn out to form small lips immediately above the vertical portion b² of the bottom plate.

Having thus described my invention, what I claim, and desire to secure by Letters Patent, is—

The design for a tongue-cap, as herein shown and described.

In testimony whereof I affix my signature in presence of two witnesses.

M. A. JOHNSON.
